Josiah C. Fay, of Troy, N. Y.
M. No. 1438 Letters Patent No. 73, dated July 16, 1861.

The schedule referred to in these Letters Patent and making part of the same.

To all whom it may concern:

Be it known that I, Josiah C. Fay, of the City of Troy, County of Rensselaer and State of New York have invented or produced a new and original design for Cooking Stoves, and I do hereby declare that the accompanying drawing fully represents my design.

What I claim as my invention or production and desire to secure by Letters Patent, is the ornamental design of the stove as herein described and shown or represented in the annexed Photographic Drawing.

Witnesses.

Ex'd. A. A. Lee.
I. M. Augustus R. Grant.
